US0D1076869S

(12) **United States Design Patent** (10) Patent No.: **US D1,076,869 S**
(45) Date of Patent: ** May 27, 2025

(54) **EARPHONE**

(71) Applicant: **SONY INTERACTIVE ENTERTAINMENT INC.**, Tokyo (JP)
(72) Inventor: **Daisuke Kurihara**, Chiba (JP)
(73) Assignee: **SONY INTERACTIVE ENTERTAINMENT INC.**, Tokyo (JP)

(**) Term: **15 Years**

(21) Appl. No.: **29/906,191**

(22) Filed: **Nov. 1, 2023**

(30) **Foreign Application Priority Data**

Jun. 9, 2023 (JP) ..... 2023-011838 D

(51) **LOC (15) Cl.** **14-01**

(52) **U.S. Cl.**

USPC **D14/223**

(58) **Field of Classification Search**

USPC D14/223; D24/174; 128/864-866;
D13/108; 381/380-381, 322, 328

CPC H04R 1/10; H04R 25/00; H04R 1/1066;
H04R 1/1016; H04R 5/033; H04R

5/0335; H04R 1/1091

(57) **CLAIM**

The ornamental design for an earphone as shown and described.

DESCRIPTION

FIG. 1 is a perspective view of front, top and left side of an earphone showing my new design;

FIG. 2 is a perspective view of rear, bottom and left side thereof;

FIG. 3 is a perspective view of top and left side thereof;

FIG. 4 is a perspective view of bottom and right side thereof;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines depict portions of the earphone that form no part of the claimed design.

1 Claim, 10 Drawing Sheets
